(Cl. D9—2)

To all whom it may concern:

Be it known that I, Clarence Karstadt, a citizen
of the United States, residing at Glen Ellyn, in
the county of Du Page and State of Illinois, have
invented a new, original, and ornamental Design
for a Portable Vacuum Cleaner, of which the fol-
lowing is a specification, reference being had to
the accompanying drawings, forming a part
thereof, in which:

Fig. 1 is a side elevation of the new portable
vacuum cleaner; Fig. 2 is a plan view thereof;
Fig. 3 is a side elevation of the new portable
vacuum cleaner showing the side opposite to
that shown in Fig. 1; and Fig. 4 is a front eleva-
tion thereof.

This application is a continuation of my co-
pending application Serial No. D. 4,187, filed
July 28, 1949, now abandoned, which was a con-
tinuation of application Serial No. D. 150,443,
filed December 30, 1948, now abandoned, which
was a continuation of my application Serial No.

D. 146,708, filed January 1, 1948, and now
abandoned.

I claim:

The ornamental design for a portable vacuum
cleaner, as shown and described.

CLARENCE KARSTADT.
